his ATTORNEY:

UNITED STATES PATENT OFFICE.

HENRY A. HOUSE, OF BRIDGEPORT, CONNECTICUT.

AIR-PRESSURE AND VACUITY INDICATOR.

No. 817,778.

Specification of Letters Patent.

Patented April 17, 1906.

Application filed May 2, 1905. Serial No. 258,476.

To all whom it may concern:

Be it known that I, HENRY A. HOUSE, a citizen of the United States, and a resident of Bridgeport, in the county of Fairfield and 5 State of Connecticut, have invented certain new and useful Improvements in Air-Pressure and Vacuity Indicators, of which the following is a specification.

My invention relates to gages adapted to 10 indicate pressures, speeds, vacuity, and the height of liquid in storage-tanks; and it consists of a registering-glass, a flexible liquid-holding reservoir located at one end of the glass, and a flexible air-reservoir located at 15 the other end. Said reservoirs are located within chambers, into one of which air is forced to compress the flexible fluid-holding reservoir to force the liquid up into the registering-glass and the air from the glass into 20 the flexible air-reservoir at the top, thus permitting the liquid to flow freely up the glass. When the device is thus used as a pressure-gage, the upper chamber is provided with an air-outlet, so that the flexible air bag or 25 reservoir at the top will be free to expand under the incoming air from the registering-glass. When indicating vacuity, the process is reversed. The air is exhausted from the upper chamber to allow the flexible reservoir or 30 bag in said upper chamber to expand, which will cause the liquid from the lower flexible reservoir to flow up the registering-glass, and thus indicate the degree of vacuity.

To enable others to understand my invention, reference is had to the accompanying 35 drawings, in which—

Figure 1 represents a front elevation of the indicator. Fig. 2 is a rear elevation of the indicator and a broken view of a flexible tube 40 connected with a metal tube opening into the chamber surrounding the flexible fluid-reservoir. Fig. 3 is a detail upper plan view of the top bracket of the indicator with the cap or casing removed. Fig. 4 is a broken sectional view of the registering-glass, a view of the air-reservoir located above the glass, sectional view of its support, broken sectional view of a tube connected therewith, sectional view of the support for the lower end of the 45 registering-glass and the flexible fluid-reservoir, broken sectional view of the cap surrounding the fluid-reservoir, and broken sectional view of a tube opening into the interior of said cap. Fig. 5 is a sectional view of the indicator on line 5 of Fig. 1. Fig. 6 is a detail edge elevation of one of the flexible 50

reservoirs and an elevation of its support. Fig. 7 is a detail view of one of the flexible reservoirs attached directly to a broken portion of the registering-glass.

60

Its construction and operation are as follows:

1 is the registering-glass.

2 is a supporting-base for the lower end of the glass. A central recess, Fig. 4, is provided in the upper surface of this base to receive the packing-washer 3, on which the lower end of the glass rests.

65

4 is a projection on the under side of the base 2, about which is tightly secured the neck portion of the bag-like reservoir 5. This reservoir is made of rubber or other flexible material adapted to hold colored liquid for registering purposes, as will be hereinafter more fully explained. The projection 4 has a small central hole coinciding with the hole 6 of the base 2 and the hole 7 of the packing 70 75 3, whereby communication is opened between the registering-glass and flexible reservoir.

80

8 is a cap detachably secured to the base 2, the interior of which forms the chamber 9, surrounding the reservoir 5. 10 is a short tube communicating with this chamber for the purpose presently to be explained. The upper end of the registering-glass is seated on the packing-washer 10^a on the under side of the support 11. 12 is a projection of this support, about which is secured the neck of the bag-like receptacle 13 to act as an air-reservoir, presently to be explained. The packing-washer 10^a has the small hole 14, and the supporting-flange 11 the hole 15, coinciding with a hole in the projection 12 to open communication between the reservoir 90 95 13 and the registering-glass. The bracket 16 has the cup-shaped support 17, Fig. 3, adapted to receive the flange 11, Fig. 4, with the hole 18 to receive the tube 19, so that when the flange is seated in this support 17 the tubes 10 and 19 will project through their supports, as shown at Fig. 2.

20, Fig. 3, is a packing-washer adapted to underlie the flange 11. (Shown at Fig. 4.) The central hole 21 is adapted to receive the 105 circular flange portion 22, embracing the upper end of the glass 1.

23, Fig. 1, is a removable cap or casing having a chamber (not shown) like the chamber of the lower casing 8 to embrace the flexible bag-like reservoir 13.

24 is a bracket similar to the upper one, 16,

whereby the instrument is secured to the dashboard of an automobile or to any other suitable place.

In some instances it may be desirable to 5 secure the flexible reservoir directly to the registering-glass, as shown at Fig. 7.

As before mentioned, the instrument is adapted to record pressures, speeds, vacuity, and the height of liquid in storage-tanks by 10 simply changing the recording-scale 25. The scale shown at Fig. 1 represents speed, showing on the scale a reading from one mile per hour to sixty. When thus used as a speed-indicator, the tube 26, Fig. 2, connects the 15 metal tube 10 with a flexible bulb (not shown) located near the axle of a motor-vehicle, so that at each revolution of the axle or vehicle-wheel the bulb is actuated by a slight compression to send up through the 20 tube 26 and into the chamber 9, Fig. 4, short air pulsations which cause an outward pressure on the flexible fluid-holding reservoir 5. The compression of this sensitive bag-like structure will force the registering 25 liquid therefrom up into the registering-glass. As the speed of the vehicle increases the more rapid will be the air pulsations and the farther the liquid will flow up the recording-glass. As soon as the liquid starts to move 30 up into the glass it will displace the air therein and force it up into the upper flexible reservoir 13 and expand such reservoir in proportion to the height of liquid in the registering-glass. To allow the upper reservoir 35 to expand freely, the air in the upper chamber surrounding said reservoir is allowed to escape through the vent-pipe 19. Were it not for this vent the air in said upper chamber would be more or less compressed by the 40 expansion of the reservoir 13 and cause more or less back pressure on the registering fluid in the glass, and thus interfere with a correct reading. If the speed is greater than can be indicated on the scale or when the instrument 45 is used for indicating pressures and the pressure is greater than can be indicated, the liquid simply flows into the upper air-reservoir and when the pressure is removed falls back into the lower reservoir again. It will 50 thus be seen that there is no possible chance to overflow the recording liquid, and thus render the instrument worthless until such liquid is replenished. The instrument can be reversed or placed in any position and not 55 a drop of the liquid can escape.

When using the device for indicating pressures, the only change necessary from the above description will be the registering-scale. When using the device to indicate the 60 height of fluid in a storage-tank, (not shown,) both of the tubes 10 and 19 are connected with the tank and a suitable scale used. When using the device to register the amount of vacuity, the connection is made with the 65 upper tube 19, which then becomes a suction-

tube, while the lower tube 10 is open to the atmosphere. When thus connected, the air will be exhausted from the upper chamber (not shown) in the cap 23, which will create a vacuum in said chamber. Relieved of outward pressure, the air in the upper reservoir will expand and form a partial vacuum in the registering-glass, and the liquid in the lower reservoir will flow up into this glass and indicate the amount or degree of vacuity in any 75 vessel with which the instrument is connected. As the reading of the instrument for any of the desired purposes above described depends on air-pressure and a registering liquid, the instrument can be set at any distance from the object with which it is connected.

The above-described device has many advantages over the ordinary fluid-indicators. In the first place the fluid cannot overflow, 80 for an excess of pressure will only force the liquid from one flexible reservoir into the other flexible reservoir, and when one is emptied there can be no further pressure on the exhausted reservoir that will affect the 85 liquid in the reservoir into which such liquid has been forced. In other words, when the lower reservoir is completely collapsed and the communication between it and the glass tube fully shut off there can be no further 90 pressure on the liquid in the upper reservoir to rupture the same by an overpressure.

My device is particularly adapted to use alcohol, which is the most sensitive and best of all the fluids for registering purposes, as 100 there is no loss due to evaporation, as it is effectually excluded from the atmosphere. The flexible nature of the reservoirs renders them very susceptible to any outer disturbance of the atmosphere whether such disturbance is due to pressure or vacuum in the chambers surrounding said reservoirs. In my device there are no mechanical appliances like, for instance, valves or springs to 105 get out of order.

Another advantage of my peculiar construction is the manner in which the glass tubes are held in place on their supports, so that when a glass is accidentally broken it can readily be replaced by another.

Having thus described my invention, what I claim as new, and desire to secure by Letters Patent, is—

1. In an indicator of the character described, a glass tube, flexible reservoirs having open communication with the interior of said tube and at each end thereof, said reservoirs and tube sealed against the admission of air, a casing to form a chamber about each reservoir, one of said reservoirs holding liquid, means for admitting air above the normal into one chamber to force the liquid into the glass, and means to permit the escape of air from the other chamber, for the purpose set forth.

2. In an indicator of the character described, a glass tube, supports at each end thereof, packing between the ends of said glass and supports, projections on said supports, flexible reservoirs connected with said projections and having open communication with the interior of the glass, a casing to form a chamber about said reservoirs subject to pressure or vacuity, means for communicating with said chambers, for the purpose set forth.
3. In an indicator of the character described, an indicating-tube, flexible air and liquid holding reservoirs communicating with the interior of said tube and located one at each end thereof so as to seal the interior of said reservoirs and tube against the atmosphere or outer air, one of said reservoirs adapted to expand while the other is contracting so that, when the liquid is rising in the tube from the liquid-holding reservoir, the other reservoir will be expanded by air in advance of the rising liquid in the tube and thus avoid air compression above said liquid and also prevent the overflow of the liquid, for the purpose set forth.
